UNITED STATES PATENT OFFICE.

EMERALD E. JONES, OF CHICAGO, ILLINOIS.

SAW-GUARD.

1,255,886.

Specification of Letters Patent. Patented Feb. 12, 1918.

Application filed November 23, 1915. Serial No. 62,993.

To all whom it may concern:

Be it known that I, EMERALD E. JONES, a subject of the King of England, and a resident of the city of Chicago, county of Cook, and State of Illinois, have invented certain new and useful Improvements in Saw-Guards, of which the following is a specification.

My invention has for its object the production of a device of this character especially designed for use in connection with a saw machine in which the bed thereof is angularly adjustable.

A further object is the production of a saw guard as mentioned which will be highly efficient in use and of durable and economical construction.

Other objects will appear hereinafter.

The invention consists in the combinations and arrangements of parts hereinafter described and claimed.

The invention will be best understood by reference to the accompanying drawing, forming a part of this specification, and in which—

Figure 1 is a front elevation of a saw machine equipped with a saw guard embodying the invention.

Fig. 2 is a side elevation of the construction shown in Fig. 1, the lower portion of the base of the machine being broken away,

Fig. 3 is a rear elevation of the guard proper detached,

Fig. 4 is an end elevation thereof,

Fig. 5 is a top plan view thereof,

Fig. 6 is a sectional detail view illustrating the connection between the guard proper and the guide rods,

Fig. 7 is a detail vertical section illustrating the connection between the two vertical elements of the guard proper which permits of free vertical movement of one of said elements relative to the other, and

Fig. 8 is an enlarged detail section taken on line $\alpha-\alpha$ of Fig. 7.

The preferred form of construction as illustrated in the drawings is shown employed in connection with a saw machine comprising a base 1, a bed 2 mounted for angular adjustment upon said base and a saw blade 3 which projects through and above the bed 2 in the usual manner.

The guard mechanism forming the subject matter of this application comprises a supporting element which comprises a

pair of spaced parallel bars 4 rigidly secured in and projecting from a plate 5 which is rigidly fastened to the base 1 of the saw machine at the rearward side thereof. Upon the outer ends of the members 4 is adjustably mounted a yoke 6 secured thereto by means of set screws 7. Mounted in the yoke 6 is a second pair of spaced parallel vertically adjustable bars 8 secured in positions of adjustment in yoke 6 by means of set screws 9. The upper ends of bars 8 are rigidly connected by means of a yoke 10 in which are adjustably mounted forwardly projecting spaced parallel bars 11 secured in positions of adjustment in said yoke 10 by means of set screws 12. At the forward ends of bars 11 is supported a yoke 13 upon the front side of which is mounted a plate 14, the latter being pivotally secured to said yoke by means of a forwardly projecting cap screw 15 threaded in said yoke and which projects through said plate, the head 16 of said screw engaging against the front side of said plate. Also projecting forwardly from the yoke 13 are two diametrically positioned studs 17 adapted for engagement with either of the two sets of correspondingly positioned perforations formed in plate 14 as clearly shown in Fig. 1. The arrangement is such as will be seen that provision is made whereby the plate 14 may be locked in either of two positions through engagement of the studs 17 with said perforations. In the disengagement of said plate from said studs 17 in order to permit of the adjustment of the former, it is of course necessary to sufficiently loosen the screw 15 to permit of the release of said plate from the outer ends of said studs. The utility of this adjustment will appear as the description proceeds.

Carried by the plate 14 is a pair of spaced parallel guide rods 18 upon the outer ends of which is mounted the saw guard proper. Said saw guard proper comprises two spaced parallel vertically disposed elements or plates 19 and 20, the element 19 being rigidly fastened by means of fastening devices 22 to an engaging element 21 in which are formed openings 21' and 21'' for engagement with the outer ends of guide rods 18. The element 21 is formed in two half parts which are connected together by bolts 23 and coöperating nuts, rollers 24, as clearly shown in Fig. 6, being loosely mounted on 110

said bolts for engagement with the corresponding guide rods 18 in order to alleviate friction.

Arranged outwardly of the element 21 is 5 a vertically disposed blade 25 having rearwardly projecting lugs or flanges 26 which overlap with the lower portion of the element 21, being fastened thereto by means of headed bolts 28 threaded into said element 10 21 as clearly shown in Fig. 8. The lugs 26 are provided with elongated transversely extending slots 27 for registration with the bolts 28 in order to permit of adjustment of the plate 25 toward and from the element 19, 15 upon unscrewing of the bolts 28, as will be readily understood. Also formed upon the upper side of the base portion of element 21 are ribs 29 which engage with the slots 27 in order to maintain the parallel relation of 20 plate 25 with the element 19 in the adjustment of said parts toward and from each other. The upper ends or heads of bolts 28 are provided with square sockets or recesses as seen for the reception of a key in the 25 rotative adjustment of said bolts.

The plate 25 serves merely as a support for the guard element 20, said plate being provided adjacent its ends with two sets of forwardly projecting studs 30 which loosely 30 engage with vertically extending elongated slots 31 formed in the element 20 as clearly shown in Figs. 1, 3 and 7. In order to hold the element 20 in position upon said studs plates 32 are fastened upon the outer ends of 35 said studs which loosely engage against the front side of said element as will be readily understood. Upon said studs 30 are provided rollers 33 adapted to engage against the sides of slots 31 in order to alleviate friction 40 and thus permit of free vertical movement of element 20 relative to the element 19. Formed at the front ends of elements 19 and 20 are inclined surfaces 34 which serve to guide the work passed over the bed 45 of the saw machine under said elements 19 and 20, the latter being pushed upwardly by the work in this operation as will be readily understood.

When the guard mechanism is applied to 50 a saw machine the elements 19 and 20 assume positions at opposite sides of the saw blade thus serving as effectual means of guarding the same. The loose mounting of the element 21 upon the guide rods 18 allows the guard to slide upwardly thereon in 55 the passage of the work over the bed of the machine. By reason of the free vertical movement permitted the element 20 relative to the element 19 it will be seen that no matter 60 what inclination the bed 2 may be adjusted to, both of said elements will always

be in contact with the machine bed so as to preclude the possibility of the fingers of the worker passing under the guard to engagement with the saw blade. The adjustment 65 which is permitted the element 20 toward and from the element 19 by adjustment of bolts 28 is of course of advantage in adjusting the guard to the saw blade, the adjustment which is permitted the supporting elements 8 and 11 being also of utility in the latter connection. Through the rotary adjustment which is afforded the plate 14 and the releasable locking effected by studs 17, the guide rods 18 may be rotated upwardly 70 through an angle of ninety degrees and locked in this position in order to support the guard in an elevated position above the bed of the saw machine when the guard is not in use. 80

While I have illustrated and described the preferred form of construction for carrying my invention into effect, this is capable of variation and modification without departing from the spirit of the invention. I, 85 therefore, do not wish to be limited to the precise details of construction set forth, but desire to avail myself of such variations and modifications as come within the scope of the appended claims. 90

Having described my invention what I claim as new and desire to secure by Letters Patent is:

1. The combination with a saw machine comprising a bed and a saw blade projecting 95 through and above said bed, of a guard comprising two spaced elements adapted to engage against the upper side of said bed at either side of said saw blade, one of said elements being free for vertical movement relative to the other, and said elements being adjustable toward and from each other, substantially as described.

2. The combination with a saw machine comprising a bed and a saw blade projecting 105 through and above said bed, of a guard comprising two spaced elements adapted to engage against the upper side of said bed at either side of said saw blade; elongated slots provided in one of said elements; and studs 110 projecting from the other element loosely engaging in said slots to permit of free vertical movement of one of said elements relative to the other, substantially as described.

In testimony whereof I have signed my 115 name to this specification in the presence of two subscribing witnesses.

EMERALD E. JONES.
